UNITED STATES PATENT OFFICE

2,673,008

DISPENSER.

Richard W. Ryan, Brooklyn, N. Y.

Application July 26, 1950, Serial No. 175,993

3 Claims. (Cl. 222—162)

1

This invention relates to a receptacle mountable upon the wall of a closet or room, and adapted to support a container in which is a supply of a deodorant, moth preventive, air sweetener, or other substance maintained in said container under pressure and adapted to be released in a spray jet upon opening of a valve with which said container is equipped.

The main object of the present invention is to provide an improved receptacle of the character described that will be of simple, attractive, molded composition; will be readily mountable at any desired location; will cause the opening of the container valve with speed and facility; will be specifically adapted to support valved containers of well known make and design; and will permit the swift and easy insertion or removal of a container.

With the foregoing and other objects in view which will appear as the description proceeds, the invention consists of certain novel details of construction and combinations of parts herein-after more fully described and pointed out in the claims; it being understood that changes may be made in the construction and arrangement of parts without departing from the spirit of the invention as claimed.

Referring to the drawing

Figure 1 is a perspective view, portions being broken away, of a wall receptacle formed in accordance with the present invention, a container of well known make and design being shown in proper position therein.

Fig. 2 is a vertical section through the wall receptacle constituting the present invention, the container being shifted to valve opening position.

Referring to the drawings in detail, the wall receptacle includes a supporting bracket preferably of molded construction, and formed with the flat plate-like body 1 adapted to be positioned against any vertical surface such as a closet wall, not shown, said flat body 1 being formed with the parallel vertically extending inturned guide flanges 2 extending from top to bottom of opposite sides of said body.

In the present instance, the body 1 is formed with the vertically spaced openings 3 adapted to receive screws or other fastening elements, not shown, whereby said body 1 is adapted for mounting upon a wall surface. I believe it will be readily apparent that instead of the openings 3, other means for attaching the bracket to a wall surface can be provided, it being mainly important that some suitable means be utilized

for supporting the bracket upon a wall surface at a location where it will be readily accessible to a user.

At their lower ends, the guide flanges 2 may be pinched together or formed with end abutments 4, so as to narrow or close completely the bottom ends of the guide flanges so as to preclude the accidental dropping of the container support 5 to be engaged by said flanges.

10 The container support 5 may be of any cross sectional configuration, so as to correspond generally with the cross sectional configuration of a container to be mounted therewithin. In any event, in the present instance a cylindrical container is illustrated, and accordingly, the container support 5 is of approximately half round cross sectional shape, being formed with an open back so that the container can be inserted in said container support from the back thereof, prior to dropping of the container support into place upon the supporting bracket. Obviously, after the container support is dropped into place, the normally open back portion thereof will be closed by the flat plate-like body 1.

25 Extending vertically of its opposite sides, at the back of the container support, are the outturned longitudinal flanges 6, proportioned to be received in the slideway defined by the inturned guide flanges 2.

30 Thus, when the container support is to be positioned upon the bracket as in Fig. 1, the flanges 6 of said support are inserted in the upper ends of the guide flanges 2, and the container support is then slidably lowered into proper position.

35 The container support is formed with a closed bottom 7, on which the dispensing container is normally positioned, and the closed bottom is formed medially and forwardly thereof with a small slot or opening 8, receiving a tiltable pressure lever including the tongue 9 normally supported between the bottom of the container and the bottom 7 of the container support, said tongue being at right angles to and integral with a depending portion 10 that projects downwardly through the slot 8 so as to be readily accessible to a user who, in tilting or pivoting the lever, presses his thumb T against the depending portion, thus to tilt the lever to the position illustrated in Fig. 2.

40 45 50 At its upper end, the container support is formed open except for the provision of a cross bar or abutment 11 integral with the container support and extending across the back portion thereof as readily seen from Fig. 2. Intermediate its ends the abutment 11 is formed with the

spaced apart depending guide projections 12, so as to insure proper positioning of the upper end of the container 13. At this point, it will be understood that the container 13 does not per se constitute any part of the present invention, the present invention being mainly directed to the provision of a wall support for said container that is particularly adapted for meeting, with respect to the particular make of container, the several purposes hereinbefore announced.

In any event, the container 13 is provided at its upper end with the upstanding yoke 14 of inverted U shape, open at front and rear as at 15 and formed with the opening 16 that opens upwardly through the top portion of the yoke. Slidably positioned through the opening 16 is the plunger 17 of the valve mechanism 18. Normally, one using the particular dispensing container 13 would press downwardly upon the plunger 17 with his or her thumb, so as to cause a spray jet to issue from the container. By use of the wall support constituting the present invention, however, the same result is achieved by pressing forwardly upon the depending portion 10 of the bottom lever, thus to impart upward movement to the container 13 within the support, thereby causing the top end of the plunger 17 to be engaged by the under side of the cross bar or abutment 11. As a result, the plunger 17 is depressed, the valve is opened, and the spray jet is directed forwardly through the large front opening 19 formed in the container support at its upper end.

When it is desired to replace an empty container, the container support is simply slid upwardly off the supporting bracket, thereby exposing the open back portion of the support and permitting easy removal of the empty container through the open back of said support. A new container is then properly positioned by insertion through said open back, and the support again returned to place upon the supporting bracket on the wall.

What is claimed is:

1. A well receptacle for a dispensing container having a depressible valve plunger at its upper end, comprising a wall bracket including a flat plate-like body, guide flanges extending down opposite sides of said body, a container support including side flanges receivable in the first 50 named flanges for removably attaching said container support to said body, said container support being proportioned to receive a dispensing

container and having an open back through which said container is insertable and removable, said open back being closed by the flat plate-like body, an abutment at the upper end of said support, and a tiltable lever mounted at the lower end of said support and adapted to be pressed upwardly against a container positioned within said support for forcing said container upwardly into engagement with said abutment for depression of the valve plunger.

2. A wall receptacle for a dispensing container having a depressible valve opening plunger at its upper end, said receptacle comprising a vertically disposed wall plate, a container support 15 detachably carried by the wall plate, a bottom wall carried by and closing the lower end of the container support, a plunger engaging abutment carried by the container support adjacent the upper end thereof, and manually actuated means 20 carried by the bottom wall and engaging the bottom of a dispensing container mounted in the container support for elevating the container and causing the depressible plunger thereof to engage the abutment and be depressed into the dispensing container.

3. A wall receptacle for a dispenser having a valve opening plunger at one end thereof, said receptacle comprising a wall plate, a container support detachably carried by said wall plate, a wall carried by and closing an end of said container support, a plunger engaging abutment 30 carried by the container support adjacent the opposite end thereof, and manually actuatable means carried by said first mentioned end of said container support engaging the dispensing container remote from said valve opening plunger for moving the container in said container support to engage the plunger with said abutment to be moved to valve opening position.
